UNITED STATES PATENT OFFICE.

MAX GRUBENMANN, OF ZURICH, SWITZERLAND, ASSIGNOR TO ALUMINUM-SCHWEISSWERK A.-G., OF SCHLIEREN, SWITZERLAND.

HEAT-EXCHANGE DEVICE FOR TREATING MILK, WORTS, AND THE LIKE.

1,423,794.

Specification of Letters Patent. Patented July 25, 1922.

Application filed July 5, 1921. Serial No. 482,511.

To all whom it may concern:

Be it known that I, MAX GRUBENMANN, residing at Zurich Hirschengraben 60, Zurich, Switzerland, have invented a new and useful Improvement in Heat-Exchange Devices for Treating Milk, Worts, and the like, of which the following is a specification.

This invention relates to improvements in the construction of heat exchange devices for milk, worts and the like, of the type in which the liquid to be cooled flows downwards as a film over the exterior surfaces of two sheets of metal, spaced a short distance apart, while the cooling liquid, such as water or brine, flows through the space between the plates.

The metal aluminium, owing to its high heat conductivity and the absence of any deleterious action upon liquids of the kind referred to, would appear to be a highly suitable material for the construction of such heat exchange devices, but its employment has hitherto been prevented by the peculiar difficulties in working the metal. For the treatment of milk and other liquids liable to putrefactive or other changes due to the activity of micro-organisms, it is essential that flanged or riveted joints or any construction affording crevices for the lodgment of micro-organisms should be avoided, whilst the use of solder is prohibited by the danger of contamination of food products with lead, as well as by the comparative weakness of the joints and the tendency to electrolytic action. For these reasons autogenous welding has been the only method which could be contemplated for the construction of such apparatus; but the hitherto insuperable difficulty in satisfactorily welding together the edges of the two sheets in order to make the watertight joints required has prevented its adoption. It is necessary for the satisfactory working of such heat exchange devices that there should be no distortion of the plates, that the adjacent sinuosities of the two opposed plates should follow each other uniformly and closely, and that the surface should be free from local imperfections such as raised or hollow spots; otherwise the liquid does not flow evenly over the whole surface, for example, it does not flow over the raised parts of the surface which are thus inoperative, or it falls from them in drops

instead of adhering as a film. When, however, it is attempted to weld autogenously in the known manner the edges of the two sheets so as to make a watertight joint, the expansion of the metal under the action of the blow-pipe flame causes warping and distortion to occur and when the joints are completed the surfaces in their neighbourhood exhibit imperfections of the kind referred to.

According to the present invention in the construction of heat exchange devices of the type referred to from sheets of aluminium arranged parallel to one another and spaced a short distance, for example, 4 to 6 millimetres apart, there is inserted between the sheets near the edges to be joined an aluminium wire or rod of corresponding diameter bent to the same contour as and snugly fitting between the sheets. The two sheets thus spaced apart and firmly held, as, for example, by tacking at suitable intervals in the known manner, are then welded together autogenously along the edges to form a watertight joint, the presence of the wire or rod rendering the operation comparatively easy. Distortion and blemishes of the kind above referred to are thus avoided and the joints have a pleasing appearance. The presence of the wire or rod imparts rigidity to the finished article.

The space between the sheets and the diameter of the wire or rod may be chosen according to the velocity at which it is desired the cooling liquid shall flow through them.

The invention although herein described as applied to sheets of aluminium may also be applied to sheets of other metals or alloys which like aluminium are suitable for the construction of heat exchange devices and are capable of being autogenously welded but offer difficulties under the action of the blow pipe similar to those offered by aluminium when attempts are made to weld them without the interposition of a wire or rod as aforesaid.

The invention is illustrated in the accompanying drawing, Figure 1 of which is a vertical section through a heat exchange device, Figure 2 a side view with one side of the casing removed, Figure 3 a part plan and part horizontal section and Figure 4 a part vertical section.

A, A, are two corrugated metal sheets and

B is a wire or rod of the same metal which is bent to the same contour as that of the sheets and is inserted between them at their edges, after which the sheets are automatically welded to the wire. The top and bottom edges of the sheets are welded to horizontal pipes C, C, which are also formed of the same metal; the lower pipe C to which cooling liquid may be supplied has a series 10 of holes formed in it through which the liquid can rise into the space between the sheets A, while the upper pipe C has likewise a series of holes in it so that the liquid may pass from the space between the sheets into the 15 pipe and so away.

The cooling body composed of the sheets and pipes is mounted in a vertical casing D at the top of which is a trough E having in it perforations F through which the liquid

which is to be cooled and which is delivered 20 to the trough can flow on to the top of the upper pipe C and then down the outer surfaces of the two sheets A into a trough G at the bottom.

What I claim is:—

In a heat exchange device, the combination 25 of a pair of corrugated metal sheets, wires of the same metal fitting between the corrugations at opposite edges of the sheets, the sheets and the wires being welded together, and pipes welded to the other edges 30 of the sheets and having in them orifices communicating with the space between the sheets.

In testimony that I claim the foregoing 35 to be my invention, I have signed my name this 15th day of June, 1921.

MAX GRUBENMANN.
